ELECTRON TUBE

Original Filed Aug. 19, 1943

UNITED STATES PATENT OFFICE

2,477,667

ELECTRON TUBE

Walter Soller, Cincinnati, Ohio, assignor of one-half to William H. Woodin, Jr., San Mateo, Calif.; Nora A. Woodin, executrix of said William H. Woodin, Jr., deceased

Original application August 19, 1943, Serial No. 499,260. Divided and this application August 28, 1944, Serial No. 551,514

6 Claims. (Cl. 250—174)

1

My invention relates broadly to electron tubes and more particularly to a deflection type of secondary electron emission tube for wide application in the electronic industry.

This application is a division of my application Serial No. 499,260 filed August 19, 1943 for Electron tube.

One of the objects of my invention is to provide a construction of deflection type secondary electron emission tube having associated input and output circuits wherein substantially complete isolation of the input from the output circuit is effected.

Another object of my invention is to provide an improved construction of secondary emission electron beam controlled tube having a pair of apertured disc-like focusing electrodes for accurately controlling the movement of an electron beam of circular section with respect to a secondary electron discharge electrode assembly.

A further object of my invention is to provide a secondary electron discharge tube having an arrangement of electrodes in which a high degree of sensitivity is obtained by effecting a large change in secondary electron emission for a slight change in deflection of an electron beam.

Still another object of my invention is to provide a construction of secondary electron discharge electrode assembly comprising an annular hooded collecting plate and an annular disc-like secondary electron emitting plate disposed therein in association with a grid electrode and disc-like plate collecting electrode.

Other and further objects of my invention reside in the construction and arrangement of the elements of deflection type secondary electron emission tubes as set forth more fully in the specification hereinafter following by reference to the accompanying drawings, in which:

Figure 1 is a longitudinal sectional view through the secondary emission tube of my invention showing the disc-like focusing electrodes and the secondary discharge electrode assembly against which the focused beam is directed; Fig. 2 is a transverse sectional view taken on line 2—2 of Fig. 1; Fig. 3 is a transverse sectional view taken on line 3—3 of Fig. 1; Fig. 4 is a longitudinal sectional view taken through a modified form of secondary emission tube embodying my invention and showing an annular plate electrode having an aperture therein of larger size than the structure shown in Figs. 1—3 utilized in conjunction with a conventional type of sweep control for the beam tube; and Fig. 5 is a transverse sectional view taken on line 5—5 of Fig. 4.

2

In Figs. 1—3 I have shown the system of my invention applied to an electron beam amplifier tube. I have termed this an electron beam amplifier tube rather than a deflection tube because

5 in this arrangement I provide an electron beam generator of the electron gun type schematically represented at 104, which propagates an electron beam of circular section through the apertured electrodes 105 and 106. Apertures are indicated 10 at 105a and 106a. The apertured electrodes 105 and 106 are curved as shown, and are connected to the input circuit 40 and serve as focusing electrodes for the electron beam propagated from electron gun 104. As the current changes in the 15 input circuit 40, the beam is caused to change from an accurate focus to an out of focus condition.

The electron beam is directed toward the disc-like secondary electron emitting plate member

20 108, centrally apertured at 108a as shown in Fig. 3. The disc-like secondary electron emitting plate 108 is surrounded by a flared cylindrical collector electrode 109, shaped as indicated. The electrode 109 also encloses grid electrode 54 and

25 is spacially related to plate electrode 55. The electron beam striking plate electrode 55 when passing through aperture 108a does not cause the emission of electrons from the annular disc-like plate 108 but when the beam is drawn over

30 against the surface of annular disc-like secondary electrode 108 the electronic bombardment causes the emission of secondary electrons that are drawn over to the flared cylindrical collector electrode 109. The original beam is circular in

35 cross section as it is formed and it is propagated from electron gun 104 and passes through the apertures 105a and 106a in focusing electrodes 105 and 106 and through aperture 108a in electrode 108.

40 The potential on the two input plates 105 and 106 allows the beam to focus exactly in the center of the plate 108 and, therefore, passes through the aperture 108a in plate 108 and strikes plate electrode 55. Any secondary electrons

45 which would be emitted remain there because grid 54 is held at a negative potential by battery 57. As the input increases the beam of electrons is thrown out of focus by the voltage on the two circular spherical shaped plates 105 and 106.

50 This changes the focus of the beam so that it now does not focus in the aperture 108a in the plate 108 but is spread out as it strikes plate 108. The extent of this spreading out is controlled by the input potentials on plates 105 and 55 106. In this way a similar result is obtained

as with the deflection method, although I do not limit my invention to deflection and can use any means by which a change in emission from plate 108 can be secured to the output circuit. Accordingly it will be understood that my invention is not restricted to a rectangular cross section beam but is equally applicable to a circular section beam.

In Figs. 4 and 5 I have shown my invention applied to an electron beam tube in which an electron beam of circular section emanating from electron gun 104 may pass through an enlarged aperture 115 in the disc-like secondary electron emitting plate 114 and be displaced under control of deflection plates 7-8 to strike the annular face of plate 114 for release of secondary electrons to the flared cylindrical collector plate 109. The structure illustrated in Figs. 4 and 5 differs from the structure described in Figs. 1-3 by reason of the enlarged aperture 115 in plate 114. Greater sensitivity is obtained by enlarging the aperture in plate 114 as a large change in secondary emission is secured by a slight change in the deflection of the beam. The arrangement of the electrodes in the tube of Figs. 4 and 5 and the circuits interconnecting said electrodes are similar to the arrangement shown in Figs. 1-3.

The secondary emission electron beam tube of my invention has wide application in electrical control circuits and is applicable to regenerators, oscillators, feed-back circuits, reverse feed-back circuits, D. C.-A. C. amplification systems and various forms of frequency multipliers or frequency division systems. The outstanding advantage of the electron beam tube of my invention is complete isolation of the input circuit from the output circuit to meet such conditions, for example, as low power input, high voltage amplification, high sensitivity operation or operation at high frequency. This isolation feature permits large voltages on the output with no possibility of the output voltages affecting the input; extremely low impedance not possible in the conventional grid controlled tube; and sensitivity even with large output currents.

In the form of my invention shown in Figs. 1-3 the control of the electron beam of circular section is effected by the shaped apertured electrodes 105 and 106. These electrodes are disc-like having partially spherical surfaces equidistant one from the other and formed on the radii having the same center. The electrostatic control of the electron beam that is produced by the partially spherical electrodes 105 and 106 serves to accurately center the electron beam through the aperture 108a in electron emitting plate 108 under normal conditions. Under conditions of unbalance, however, or change in electrostatic capacity between plates 105 and 106, the electron beam is angularly shifted to variably activate portions of the secondary emitting annular electrode 108 to produce the secondary emission which is collected by the flared cylindrical collector plate 109 as heretofore explained. The secondary electron collecting plate 109 is provided with an outwardly diverging skirt which is directed toward the electron beam generator and which is integral with the cylindrical portion of the electrode that surrounds the secondary electron emitting plate 108 and the grid electrode 54. This same arrangement is provided in the construction of tube shown in Figs. 4 and 5 wherein the outwardly diverging skirt of the secondary electron collecting plate 109 offers minimum interference with the primary electrons

in the electron beam propagated from the electron gun 104 while providing maximum collecting area for the secondary electrons released from the activated portions of the annular secondary electron emitting plate 114.

While I have described my invention in certain preferred embodiments, I realize that modifications may be made in the arrangement and method employed and I desire that it be understood that no limitations upon my invention are intended other than may be imposed by the scope of the appended claims.

What I claim and desire to secure by Letters Patent of the United States is as follows:

1. An electron tube system comprising an electron discharge device for propagating an electron beam, a pair of apertured electrodes disposed in the path of said electron beam for variably controlling the focus of said beam according to variations in input current, a plate system comprising a centrally apertured disc-like plate aligned with the apertured electrodes, a secondary electron emitting coating carried by the surface of said disc-like plate, a grid member mounted adjacent to said centrally apertured disc-like plate and charged at negative potential with respect thereto, a plate electrode mounted adjacent to said grid member and charged at positive potential with respect thereto, and flared cylindrical secondary electron collecting plate surrounding said disc-like plate, said collecting plate having an outwardly diverging skirt directed toward said electron discharge device out of the path of said electron beam and providing a relatively wide collecting area for secondary electrons emitted by said disc-like plate.

2. An electron discharge system comprising an electron discharge device for propagating an electron beam, means for controlling the angular sweep of the electron beam, a secondary electron emitting plate disposed in the path of said electron beam, said plate being apertured for the normal passage of said electron beam, a grid member disposed behind said plate and maintained at negative potential with respect thereto, a plate electrode mounted adjacent said grid member and aligned with said secondary electron emitting plate and maintained at positive potential with respect to said grid member, and a secondary electron collecting electrode surrounding said secondary electron emitting plate and grid member and having an outwardly diverging skirt directed toward said electron discharge device out of the path of said electron beam and providing a relatively large collecting area for receiving secondary electrons discharged by said secondary electron emitting plate under bombardment of said electron beam.

3. An electron discharge system comprising an electron discharge device for propagating an electron beam, means for controlling the angular sweep of the electron beam, a secondary electron emitting plate disposed in the path of said electron beam, said plate being apertured for the normal passage of said electron beam, a grid member disposed behind said plate and maintained at negative potential with respect thereto, a plate electrode mounted adjacent said grid member and aligned with said secondary electron emitting plate and maintained at positive potential with respect to said grid member, and a substantially cylindrical secondary electron collecting electrode surrounding said secondary electron emitting plate and grid member and having an outwardly diverging skirt directed toward said

electron discharge device out of the path of said electron beam and providing a relatively large collecting area for receiving secondary electrons discharged by said secondary electron emitting plate under bombardment of said electron beam.

4. An electron discharge system comprising an electron discharge device for propagating an electron beam, means for controlling the angular sweep of the electron beam, a secondary electron emitting plate disposed in the path of said electron beam, said plate being apertured for the normal passage of said electron beam, a grid member disposed behind said plate and maintained at negative potential with respect thereto, a plate electrode mounted adjacent said grid member and aligned with said secondary electron emitting plate and maintained at positive potential with respect to said grid member, and an annular secondary electron collecting electrode surrounding said secondary electron emitting plate and said grid member and having an outwardly diverging skirt directed toward said electron discharge device out of the path of said electron beam and providing a relatively large collecting area for receiving secondary electrons discharged by said secondary electron emitting plate under bombardment of said electron beam.

5. An electron discharge system comprising an electron discharge device for propagating an electron beam, means for controlling the angular sweep of the electron beam, a secondary electron emitting plate disposed in the path of said electron beam, said plate being apertured for the normal passage of said electron beam, a grid member disposed behind said plate and maintained at negative potential with respect thereto, a plate electrode mounted adjacent said grid member and aligned with said secondary electron emitting plate and maintained at positive potential with respect to said grid member, and an annular secondary electron collecting electrode having an outwardly diverging skirt directed to-

ward said electron discharge device out of the path of said electron beam and having a portion thereof surrounding said secondary electron emitting plate and said grid member for receiving secondary electrons discharged by said secondary electron emitting plate under bombardment of said electron beam.

6. An electron tube system comprising an electron discharge device for propagating an electron beam, a pair of electrodes disposed in the path of said electron beam for variably controlling said beam according to variations in input current, a plate system comprising a centrally apertured disc-like plate aligned with the said pair of electrodes, a secondary electron emitting coating carried by the surface of said disc-like plate, a grid member spatially related to said centrally apertured disc-like plate and charged at negative potential with respect thereto, a plate electrode mounted adjacent said grid member and charged at positive potential with respect thereto, and an annular secondary electron-collecting plate surrounding said disc-like plate, said collecting plate having an outwardly diverging skirt directed toward said electron discharge device out of the path of said electron beam and providing a relatively wide hood around said disc-like plate forming a collecting area for secondary electrons emitted by said disc-like plate.
